UNITED STATES PATENT OFFICE.

PETER TRELEAVEN, OF SAN DIEGO, CALIFORNIA.

BAG-HOLDER.

1,206,619.

Specification of Letters Patent.

Patented Nov. 28, 1916.

Application filed February 7, 1916. Serial No. 76,669.

To all whom it may concern:

Be it known that I, PETER TRELEAVEN, a citizen of the United States, residing at San Diego, in the county of San Diego and State of California, have invented certain new and useful Improvements in Bag-Holders, of which the following is a specification.

This invention relates to devices for supporting articles in convenient position for inspection or removal one at a time without disturbing the remaining articles, and has for one of its objects to provide a simply constructed device which may be suspended from a ceiling or other support in convenient position.

The improved device is designed more particularly for supporting paper bags and the like, but may be employed with slight and unimportant modifications for supporting different articles of merchandise in convenient position for display, inspection, or to enable one or more articles to be removed from the support without disturbing or disarranging the remaining articles.

With these and other objects in view, the invention consists in certain novel features of construction as hereinafter shown and described and then specifically pointed out in the claim; and in the drawings illustrative of the preferred embodiment of the invention—Figure 1 is a perspective view of one of the improved devices; Fig. 2 is an enlarged side elevation of a portion of one of the devices; Fig. 3 is a transverse section on the line 3—3 of Fig. 1.

Corresponding and like parts are referred to in the following description and indicated in all the views of the drawings by the same reference characters.

The improved device comprises a body 10 of any suitable length, and preferably constructed of wood and suspended by any suitable means as, for instance, by eyes 11 and cords 12 from a ceiling or other support, the latter not being shown as it forms no part of the present invention. The body 10 will be suspended at a convenient height above a counter or otherwise suitably located at a convenient distance above the floor or counter so that the article supported from the body may be readily reached by the clerk.

In practice the body 10 will generally be constructed from a board of hard wood and will be provided in its lower edge with a

plurality of recesses each including an upper side 13 and a vertical portion 14, the portion 13 preferably extending obliquely to the longitudinal axis of the body. As 60 illustrated the portions 13 extend from the bottom terminal of one of the vertical portions 14 to the next portion 14 in advance. The lower edge of the member 10 is thus formed into a series of recesses of the form 65 described, and any required number of recesses may be employed and of any required length. Inserted into the bottom of each recess adjacent to its vertical portion 14 is an upwardly opening hook 15, and inserted into the body 10 near the opposite end of each recess is an eye 16. The members 15—16 are preferably of the ordinary screw hook and screw eye form, as illustrated in Fig. 3. A suspension member is 70 employed for each of the recesses and each consists of a rod 17, preferably pointed at one end, as shown at 18, and with the other end bent at right angles to the longitudinal axis of the rod, as shown at 19. 80

In employing the improved device the pointed end 18 of the rod 17 is thrust through the eye 16 and the body of the rod next to the bent portion 19 engaged with the hook 15. When thus arranged the depending portion 19 will be disposed between the hook 15 and the vertical portion 14 of the recess, so that the rod is prevented from movement longitudinally thereof in one direction by the wall portion 14 and prevented from movement longitudinally thereof in the opposite direction by the hook 15. By this means each of the rods is held 90 from displacement downwardly and longitudinally and can be removed only by elevating the portion which engages the hook 15 and then moving the rod laterally to disengage it from the hook. 95

The holding devices are designed to support articles, more particularly paper bags, as illustrated at 20, in convenient position for removal by the clerk, and by employing a plurality of the supporting devices in connection with each body 10, bags or other articles of various sizes may be conveniently supported and independently accessible, as will be obvious. The bags will thus be securely supported and can be removed one at a time by tearing them loose 100 from the support 17 and without disturbing the remaining bags. When the bags are all 105 used up from any one of the holding de- 110

vices a new supply may be readily attached, as will be obvious.

The body portions 10 may be of any suitable wood, painted or otherwise ornamented, 5 while the supporting members and the eyes and hooks may be of brass or other suitable metal. The points of the rods 17 are preferably triangular transversely to facilitate their insertion through the bags.

10 Having thus described the invention, what is claimed as new is:—

A device of the class described including a body having a depending stop shoulder, an upwardly opening hook relatively near 15 the shoulder, an eye spaced from the hook, and a rod pointed at one end and with an

offset at the other end, the body of the rod being of greater length than the distance between the eye and the hook, so that when the pointed end of the rod is inserted 20 through the eye and the offset end engaged with the hook, the rod is prevented from endwise displacement in either direction by the coaction of the offset, the hook and the shoulder.

25 In testimony whereof I affix my signature.

PETER TRELEAVEN. [L.S.]
